(57) **CLAIM**

The ornamental design for a door sweep, as shown and described.

DESCRIPTION

FIG. 1 is a profile view of our new design; FIG. 2 is a top perspective view thereof; and, FIG. 3 is a bottom perspective view thereof.

The views not shown form no part of the claimed design. The dash-dot lines in the figures adjacent to the shaded areas represent unclaimed boundaries of the claimed design. The dash-dot-dot lines in the figures represent unclaimed edges and environmental elements only and form no part of the claimed design.

1 Claim, 3 Drawing Sheets(56)
